LADY'S BAG OR LIKE RECEPTACLE

Alex Hochner, New York, N. Y.

Application February 9, 1952, Serial No. 18,454

Term of patent 3½ years

(Cl. D87—3)

To all whom it may concern:

Be it known that I, Alex Hochner, a citizen of the United States of America, residing at New York, county and State of New York, have invented a new, original, and ornamental Design for a Lady's Bag or Like Receptacle, of which the following is a specification, reference being made to the accompanying drawing, forming part thereof.

Fig. 1 is a perspective view of the bag in open condition showing my new design;

Fig. 2 is a top plan view of the bag of Fig. 1 in open condition.

Fig. 3 is a bottom plan view of the bag of Fig. 1.

I claim:

The ornamental design for a lady's bag or like receptacle, substantially as shown.

ALEX HOCHNER.
